UNITED STATES PATENT OFFICE.

KENNEDY DOUGAN, OF MINNEAPOLIS, MINNESOTA.

TYPE-WRITER.

1,171,774.

Specification of Letters Patent. Patented Feb. 15, 1916.

Application filed December 27, 1913. Serial No. 808,999.

To all whom it may concern:

Be it known that I, KENNEDY DOUGAN, a citizen of the United States, and a resident of Minneapolis, in the county of Hennepin and State of Minnesota, have invented 5 certain new and useful Improvements in Type-Writers, of which the following is a specification.

This invention relates to typewriters, and 10 has for its object to provide a small, light typewriter. This object is attained by constructions which dispense with keys, key levers, and type-bars; all of the type being mounted in groups on devices carried on the 15 fingers of the operator's hands.

Figure 1 is a top view of a typewriter constructed according to the invention, portions of the ratchet-bars being broken away to expose other parts. Fig. 2 is a vertical 20 sectional view on a line II—II of Fig. 1, a portion of the printing guide being broken away. Fig. 3 is a rear elevation of the carriage-forwarding and locking mechanism, a portion of the carriage being broken away 25 and the track-rails omitted. Fig. 4 is a diagrammatic sectional elevation of a two-series type-carrier, in operative relation to a printing guide which is shown half in section. Fig. 5 is a diagram showing the 30 arrangement of the type shown in Fig. 4. Fig. 6 is a diagrammatic side elevation of the carrier shown in Fig. 4. Fig. 6^a is a detail view of several of the pinions and associated parts. Fig. 7 is a diagram. Fig. 45 8 is a top view of a printing guide like that shown in Fig. 4, also a carriage and ribbon holders. Fig. 9 is a vertical sectional view 40 on a line IX—IX of Fig. 8. Fig. 10 is a sectional detail view on a line X—X of Fig. 8, showing a type-block. Fig. 11 45 is a side elevation of a one-series type-carrier omitting the finger-clip. Fig. 12 is a detail view, a section of which, on line c—c, is shown in Fig. 10. Fig. 13 50 is a vertical sectional view of the device shown in Fig. 11, in operative relation to a type-guide 21 and selector 27. Fig. 14 is a diagram of a device hereinafter described.

Referring to the drawings in detail, 55 Figs. 1, 2 and 3, illustrate a typewriter (except the type) having a fixed platen, a carriage, a ribbon and a printing guide mounted upon the carriage, means for stepping the carriage without the usual traction spring, and an arrangement of the ribbon whereby nearly the entire line of writing

will be visible when the paper is in the machine.

The platen 1, is a longitudinal strip of platen material and is preferably square 60 in cross section. It is held in a groove formed in the ridge of a paper-support 2 which is secured to bosses 3 on the machine base 4. The transverse width of the platen 1 is slightly more than that of the largest 65 character to be printed. Adjacent the rear of paper-support 2 are two paper-feed rollers 5, 6 one of which is provided with a turning knob 7. The course of a sheet of paper through the machine is indicated on 70 Fig. 2 by a mixed line, 8.

Any suitable device for tensioning the paper may be employed. That shown consists of a sheet metal bar 9, pivotally mounted on pins 10, on which are torsion springs 75 12 having ends 12^a bearing down on said bar, and opposite ends 12^b passed through perforations in the base 4. Two tension release handles 13 are provided with a latch 14 for holding either or both of said handles 80 depressed when a sheet of paper is being inserted. A sheet passes back between posts 15, 16, 17, and under bars 18, 19, hereafter mentioned.

20 designates as a whole a carriage, in which is mounted a printing guide 21 and a pair of ribbon-spools 22, 23. The carriage 20 has rollers 24, and travels with them upon rails 26 which are supported by posts 16. The printing guide 21 as shown, is in 85 plan shape a hollow Maltese cross, the arms of which form 45 degree angles with its line of travel. The slots designated R, R will be considered as one slot in description, and the slots marked L, L will be considered as 90 one.

C, is the writing or printing center.

Slots R and L form guides for the type-carriers shown in Fig. 11 and presently described. A selector post 27 is rigidly secured 100 to the guide 21 at the slots' angle nearest the operator's side (front) of the machine. The walls 21 at each side of each slot R, L are sectionally formed as shown in Fig. 13. 28 are spacer-keys, which are integral with 105 the guide 21 and either of which are to be depressed to step the carriage and printing guide the width of a space between words. Said guide 21 is vertically movable in the carriage, with a minimum of friction, by 110 being mounted on two pairs of parallel rockable arms 29, pivoted thereto at 30 and

pivoted to the carriage at 31. Said guide 21 is drawn upward and held in a raised position, by springs 32, at a sufficient distance above the platen to permit the automatic stepping device (to be described) to be actuated by the upward movements of said guide. The vertical motion of said guide is of course curved in one direction, but said curvature does not cause any slurring of type impressions, as the arms 29 will be exactly horizontal when a type 10 strikes the paper.

Carried by the printing guide 21 are a 15 stepping pawl 33, two latches 34, 36, and a latch-releasing lever 37. Pawl 33 engages a longitudinal ratch 38 which is rigidly supported by brackets 39, secured to the back rail 26. One latch 34 engages a longitudinal ratch 40, rigidly supported by posts 17. The other latch 36 engages a longitudinal ratch 41 also rigidly supported by posts 17. The pawl 33 is drawn up against the ratch 38 by a suitable spring 42.

The operation of stepping the carriage for 25 a space or letter is as follows: Depressing the guide 21, either by a key 28 or by depressing a type-carrier in said guide, lowers the pivot 43 of a pawl 33 and permits the spring 42 to turn said pawl far enough to 30 engage it with the next tooth of the ratch 38. During said down movement of the guide 21, the latch-guide studs 44, 46 slide down in the slots of the latches, leaving said 35 latches engaged with the ratches 40, 41, whereby any end motion of the type-guide 21 during its descent, is prevented. This insures accurate alinement of the type and sharp impressions thereof. At the end of 40 said down movement, a shoulder 47 on the release-lever 37 has slipped past an incline 48 on latch 36 and reached the position shown in dotted lines, where it is caused by a spring 49 to pass beneath a shoulder 50. When the operator removes the finger from 45 key 28 or lifts a type-carrier from the guide 21, the springs 32 raise said guide, thereby lifting the release-lever bodily, said lever then lifting the latch 36, disengaging it from ratch 41. The carriage is now free to 50 move forward, *i. e.*, in the direction of the horizontal arrows. Immediately, the stepping pawl 33, as its pivot rises, begins to turn downwardly, whereby it reacts horizontally on said pivot, and moves the guide 55 21 and carriage 20 the proper distance. During the said ascent of release-lever 37, a hump 47 thereon impinges on a fixed stud 51, carried by guide 21, and the lower inclined face of said stud moves the upper 60 end of said lever forwardly, thereby causing the point of lever 37 to release the latch-shoulder 50, whereupon the latch 36 drops by gravity (or spring pressure) upon its ratch 41, then slips forward upon said ratch 65 and stops the carriage 20 by impinging upon

the next tooth ahead. During this movement the other latch 34 simply slides over one tooth of its ratch 40. To bring the carriage back to starting position, all the operator has to do is to pull a handle 52, which 70 is secured to the pawl 33, to the left. (In Fig. 3, to the right.) Said movement will simultaneously disengage the pawl 33 from ratch 38, lift latch 34 by means of nose 53 and lug 54, and draw the carriage leftwardly. Upon the release of handle 52 the pawl and latch reassume their normal positions.

56, Fig. 1, indicates an adjustable line-stop against which the carriage will impinge. 80

As shown in Fig. 1, an ink-ribbon 57 is so mounted as to cross the platen transversely. Its ends are wound on spools 22, 23, whose axial pins rest in suitable bearings in lugs 58, integral with the guide 21. 85 Spool 23 is shown as turned automatically by a resilient pawl 59 secured to the carriage 20 and positioned to turn a ratchet periphery 60 on one of the spool heads, when the guide 21 is nearing the end of an up-stroke. 90

61 indicates a holding-pawl, in Fig. 2. Tension springs 62 bear on the heads of the rear spool 22.

To insert a sheet of paper, the levers 13 are depressed, whereupon the spring latch 95 14 holds one of them down, thus holding the member 9 elevated above the plate 2. The sheet is inserted between rollers 5, 6. Then by turning the knob 7 the paper is drawn back the proper distance and the 100 tension bar 9 is lowered upon the paper with one hand while the other hand draws the paper taut over the platen.

Referring now to Figs. 4, 5, 6 and 6^a, which show diagrammatically a multiple 105 printing device, with means for selective printing. Two series of longitudinally slideable type-bars 64, each bearing on its lower end a type-block 66, are mounted in a frame comprising side plates 67, and integral top 110 and end plates 68, 69. It is desirable that the type-bars have a stroke of about $\frac{1}{2}$ of an inch or more, and to provide for such length of stroke the type-bars 64 are, preferably formed as racks, and are geared together in 115 pairs by a series of pinions 70, which are separately rotatable on a nonrotating shaft 71 whose ends are fixed in frame ends 68. All said parts are to be made as light as practicable. Normally, all the type-bars 64 are held at a uniform height by means of 120 springs 72 which as shown are connected by cords or fine chains 73 to eyes 74 on the hubs of the pinions 70.

The types are cast on square blocks 66 125 which are attached to the type-bars 64 with ball-and-socket joints 76, which however permit only a slight angular play of the type-blocks. In Fig. 4 said joints are shown diagrammatically, but a preferred actual 130

construction is shown in detail in Figs. 10 and 12. Type-bar 64 is provided with two longitudinal flanges 112. The lower end of said bar is milled out to form a seat which fits a hemispheric head 113 on the type-block 77. Secured in a kerf in head 113 is the lower end of a thin flat spring 114, whose upper end has lugs 115 that are loosely held between pairs of guide-lugs 116 struck in from flanges 112. The type-block is supported by stops 115^a on lugs 115, which stops rest upon the guide-lugs 116. This construction permits a type-block to turn slightly in any direction, which turning is likely to occur because of the carrier not being held in exactly vertical position when in use.

Owing to the large number of type that may be carried in two series on one finger, the mechanically connected pairs of type may be the capital and the "lower case" of the same letter. Or, all of the lower case characters may be carried by the right hand, as the right hand in most persons is under more perfect control and said characters are more frequent than capitals.

The frame 67—69 is provided with a finger-clip comprising, as shown here, two U shaped pieces 78 and 79, both of resilient sheet-metal. The piece 78 has ears 80 which firmly engage the sides of an inserted finger, while the piece 79 receives the tip of the finger.

Since any type-bar is alined for printing by inserting its companion in an abutment notch 102, it might be confusing to the operator, at first, if each type-bar were marked with its own character, in a place where easily seen by the operator. But such confusion may be obviated by marking each type-bar with the character printed by its companion. Fig. 14 of the drawing will make clear what is meant by this. Two type-bars, A and B, are seen in bottom plan, and are companions because connected by the pinion 70. The type-bars are provided respectively with tags 153 and 154, on which appear the added characters B and A. To print A, the bar marked A on the tag is inserted in the abutment notch 102, and to print B, the bar marked B is so inserted.

Though it is desirable to provide each finger with two series of type, arranged as shown by Fig. 5, said arrangement is not adapted for coaction with a printing guide like that shown in Fig. 1. Therefore a modification which is so adapted will now be described, the same being illustrated diagrammatically in Figs. 11 and 13. There is only one series of type-bars 82; the series of opposed rack-bars 83 are each provided with a point that is positioned to enter a conical socket in the selector post 27 of Fig. 1. Each type-bar is mechanically connected with its opposed rack-bar by a pinion 84, hav-

ing a tension spring 85 for the function aforesaid. Each rack-bar 83 is cut shorter than the companion type-bar and carries on its lower end a sticker, comprising an offset arm 88 provided with a downwardly projecting point 89. Arms 88 are offset so that, when a point 89 is inserted in the socket 81 of the post 27 the type-bar to be thrust down will stand exactly over the printing center, C. The sticker-bars 83 in the right-hand type-carriers are placed at the left of the type-bars therein, and the sticker-bars in the left hand carriers are placed at the right of the type-bars therein, when said carriers are properly positioned on the fingers. The reason will be apparent from inspection of the top view of slots R, L and post 27, Fig. 1.

Operation: Suppose the first letter to be printed is W, and that it is on a right hand finger. The operator alines the proper carrier with slot R, alines the proper stick-point 89 with the selector-post 27 and presses down quickly. The point enters the socket 81, and two guide-lugs 90, rigidly carried by the type-carrier, simultaneously pass between the beveled walls 21 of said slot R. Said guide-lugs fit the parallel faces of said walls accurately, and are slightly wider than the type-blocks, thereby relieving the latter of some friction with said faces. The descent of the type-carrier is communicated to all the parts within it, except the one sticker 88—89 and its rack-bar 83 which are upheld by the post 27; the guide 21 being still held up by the two springs 32 (Fig. 3). Hence the rack of said sticker turns the coengaged pinion 84, which drives down the associated rack or type-bar 82, double the distance traveled by the pinion shaft 86, and the type thereon stops a little below the bottom of the guide 21, by its lug 93 striking the top of the carrier frame 94. The downward stroke of the operator's finger continues, uninterrupted by said stoppage of the type-bar, thereby positively depressing the post 27 and guide 21 and causing the type to strike the paper upon the platen 1. During said stroke, all the other type-bars 82 are carried down, but only half the distance, thus they do not strike the guide-walls 21. Likewise all the other stickers 88—89 are depressed, but stop short of said walls 21.

When the type-carrier is being removed, and specifically, when the sticker 89 is being removed from the socket 81, the spring 87 which is under tension, acts through the flexible connection 96 and turns the pinion reversely, and the latter draws up the associated type-bar and depresses the said sticker.

Should a type-carrier be held slightly out of the vertical, either toward or from the hand, at the instant of printing, the type in

use will nevertheless make a flat impression upon the paper, since the pivotal joint will permit the type to adjust itself to the platen.

In the one-series form, as many as twelve characters might be provided in one carrier, this depending upon their size. If three fingers of each hand are provided with type-carriers, six type in each carrier will provide thirty-six type in all; eight on each will provide forty-eight.

In the rack and pinion construction, the function of the springs 87 may be performed by one spring acting to turn the pinion-shaft, provided said shaft has a key thereon and that each pinion has a segmental keyway permitting any pinion to be turned without turning the other pinions. Other modifications also are within the scope of the claims, which are for a plurality of movable type-pieces in a movable frame, a relatively fixed guide for guiding any type-piece printing, and means whereby a bodily movement of the frame causes any selected type to operate.

A simpler form of printing-guide than that shown in Fig. 1 is shown in Figs. 8, 9 and 10, of which Fig. 8 is a top view, Fig. 9 a vertical section, and Fig. 10 an enlarged vertical section. The printing-guide, 97, has a single, square, type-registering hole 98. In order to adapt this guide to the two-row type-carriers shown in Figs. 4 and 6, two duplicate guides and abutments 99 are provided at the respective sides of the guide 97, said parts 99 being secured to part 97 and straddling the bosses 100 which bear the pivot-pins 101. Each piece 99 is a thin plate having two upwardly projecting points 99, the inner edges 99^a of which are downwardly converged. The part may be otherwise described as an upwardly projecting lug 99, having cut therein a notch 102 whose downwardly converging walls 99^a form abutments for a type-block. In Fig. 10 is shown a type-block 103, positioned in the notch 102 or between the points 99. The lower edges of each type-block are beveled to prevent their cutting the abutment faces 99^a, and the notch 102 is deep enough to protect the type from striking its bottom. It is clear that the inclined sides 99^a will register a type-block toward and from the operator, and that the right and left inclined walls 104 of the guide 97 will register the companion type-block when the latter is thrust down through said guide. The right hand abutment 99 is to be used to print from a left-hand row of type, and vice versa. Any type-carrier is always to be held squarely in front of the operator, whereas with the Maltese cross form of guide they are held at easier angles.

In operation the two type-blocks at each side of the one inserted in an abutment 99 must be free to descend by a distance equal

to half the printing stroke; to permit this the abutments are cut sufficiently narrow, as shown between the arrowheads, Fig. 10.

The operator will not be compelled to hold the type-carriers in accurate alinement when writing, even if the auxiliary guide-lugs 90 are not provided on the carriers. The carrier shown in Figs. 4 and 6 has no such parts, for an obvious reason, but the writing will be regular and the impressions flat owing to the ball-and-socket joints 76. For example the type-carrier may be held at angles indicated by lines *a—a* or *b—b* Fig. 7, yet the type will be squared by passing through the type-hole 98.

Referring to the ink-ribbon 105, its spools may be arranged as shown in Figs. 8 and 9, that is, carried by the printing-guide or rather by the bosses 100 thereof. To avoid striking the paper the front spool 108 if on a horizontal axis must be small; but by mounting it as shown in dotted lines on Fig. 8 on a vertical axis held by a bracket 110, it may be as large as the back spool 106.

Having described my invention, I claim, and desire to secure by Letters Patent:

1. In combination, a manually-carried frame, a plurality of type movably mounted in said frame, and means for moving any one of said type for printing therewith by and through direct manual movement of said frame.

2. In combination, a manually carried frame, a plurality of type-bars projectably mounted in said frame, a guide for guiding any projected type-bar, type on said type-bars, and type-projecting means on said guide.

3. In combination, a manually carried frame, a plurality of type-bars projectably mounted in said frame, a guide for guiding any projected type-bar, type on said type-bars, and type-projecting means partly on said guide and partly carried in said frame.

4. In combination, a printing guide, an abutment thereon, a manually carried frame, a type-bar and an arm carried by said frame, a type on said type-bar, adapted to be guided by said printing guide, and means including said arm whereby said type is thrust into the printing guide by downward pressure of the hand upon said frame.

5. In combination, a manually carried frame, a pair of oppositely movable type-bars carried by said frame, different type on said bars, a printing guide adapted for guiding either of said type, an abutment on said guide, and means whereby either of said type is thrust into said guide by downward pressure of the hand upon said frame.

6. In combination, a manually carried frame, a plurality of type-bars bearing different type and each movably mounted in said frame, means connecting said bars in

pairs so that the bars of a pair must move in opposite directions relative to said frame, a spring yieldingly holding said bars at normal positions, a printing-guide, adapted 5 to receive one type at a time, and type-selecting means for engagement by the companion of the acting type.

7. In combination, a frame, a rackbar 82, a type-block 92 thereon, a rackbar 83, a 10 pinion meshed with both said rackbars, a spring connected to said pinion, an arm 88-89 on rackbar 83, printing guide 21, and an abutment 27 on said guide, said abutment having a socket 81 adapted to receive and 15 support said arm.

8. In combination, a frame, a pair of rackbars 64, type-blocks on said rackbars, a pinion meshed with both said rackbars, a spring connected to said pinion, a printing 20 guide 97, and an abutment 99 on said guide, said abutment having a notch 102 adapted to receive and support either of said type-blocks.

9. In combination with a manually carried type-bar, a carriage, a movable type-guide therein adapted to be depressed by operation of the type-bar, a driving pawl on said type guide and actuated by up movement of the latter, a base, a stationary ratch 25 supported from said base and engaged by said pawl, and a spring to raise said type-guide, the carriage being driven by said spring and pawl.

10. In combination with a manually carried type-bar, a carriage, a movable type-guide therein adapted to be depressed by operation of the type-bar, a driving pawl on said type guide and actuated by up movement of the latter, a base, a stationary ratch 30 supported from said base and engaged by said pawl, and a spring to raise said type-guide, means for preventing the type-guide from moving either forward or back during its down movements.

45 11. A typewriter comprising a manually-carried frame having a plurality of type-bars projectably mounted in a single line

in said frame, a platen having the width and length of a line of characters, means for holding a sheet of paper across and 50 upon said platen in such a way that the portion of said sheet upon said platen is elevated above adjacent portions of the sheet, and a guide for guiding any projected type-bar to the paper upon the platen. 55

12. A typewriter comprising a manually-carried frame having a plurality of type-bars projectably mounted in a single line in said frame, a platen having the width and length of a line of characters, means for holding a sheet of paper across and upon 60 said platen in such a way that the portion of said sheet upon said platen is elevated above adjacent portions of the sheet, an ink ribbon extending across the platen, and a 65 guide for guiding any projected type-bar upon the ink ribbon and paper on the platen.

13. A typewriter comprising a manually-carried frame having a plurality of type-bars projectably mounted in a single line in 70 said frame, a platen having the width and length of a line of characters, means for holding a sheet of paper across and upon said platen in such a way that the portion 75 of said sheet upon said platen is elevated above adjacent portions of the sheet, a carriage, a ribbon supported on said carriage and extending at right angles across the platen, a printing guide in said carriage for 80 directing the type-bar to the ribbon and paper upon the platen, and means operated by the printing guide when the same is actuated by a type-bar for moving the carriage.

14. In a typewriter, a carriage, a printing-guide in said carriage, manually carried frames, each provided with a plurality of type, means for registering any single type with said printing guide, and means for printing through said guide. 85
